UNITED STATES PATENT OFFICE.

JOHN MAJORS AND ROBERT P. FITZGERALD, OF CHARLEROI, PENNSYLVANIA.

METALLIC TIE AND RAIL-FASTENER.

No. 920,596.

Specification of Letters Patent.

Patented May 4, 1909.

Application filed October 16, 1908. Serial No. 458,015.

To all whom it may concern:

Be it known that we, JOHN MAJORS and ROBERT P. FITZGERALD, citizens of the United States of America, residing at Charleroi, in the county of Washington and State of Pennsylvania, have invented certain new and useful Improvements in Metallic Ties and Rail-Fasteners, of which the following is a specification, reference being had therein to the accompanying drawing.

This invention relates to metallic ties and rail fasteners, and the primary object of our invention is to provide a strong and durable metallic tie for supporting rails, the tie being tamped and firmly held in the ballast of a road bed.

Another object of our invention is to provide a novel rail fastener in connection with our tie for preventing lateral and vertical displacement of the rails mounted thereon.

A still further object of our invention is the provision of novel means for securing the connection of two rails upon a tie, whereby the rail connection or joint cannot shift relatively to said tie.

The present invention is an improvement upon our metallic tie for which application was filed May 14th, 1907, Serial No. 373,600, and allowed June 18th, 1908, the present improvement relating particularly to the rail fastener used in connection with the tie.

With the above and other objects in view which will more readily appear as the invention is better understood, the same consists in the novel construction, combination and arrangement of parts to be presently described and then specifically claimed.

In the drawings:—Figure 1 is a side elevation of the tie and rail fastener constructed in accordance with our invention and partly broken away, Fig. 2 is an end view of our tie, Fig. 3 is a cross sectional view of the same illustrating the rail fastener, Fig. 4 is a longitudinal sectional view of the tie and rail fastener partly broken away, Fig. 5 is an elevation of a splice bar forming part of the fastener, and Fig. 6 is a longitudinal sectional view of a portion of the tie and rail fastener illustrating a modification of our invention.

To put our invention into practice, we provide a tie of the eye-beam construction, the said tie comprising a base 1, a web 2, and a head 3, said head being enlarged at the ends of the tie, as at 4, and reinforced by vertical

oppositely disposed ribs 5, connecting the enlarged ends of the head with the base of the tie. The enlarged ends of the head 3 are cut away, as at 6, to provide seats for rails 7.

When a rail is to be simply fastened upon the seat 6, the seat is formed to provide an overhanging ledge 8 for engaging the inner base flange 9 of the rail 7, and the outer base flange 10 of said rail is held by a fastening block 11 detachably mounted upon the seat 6 by bolts 12 and nuts 13. The bolts 12 extend upwardly through the enlarged ends of the head 3 and the nuts 13 are screwed upon the upper ends of said bolts.

In order to place the fastening block 11 in position, it is necessary to slide the same in from one side of the tie on account of the beveled end 14 of the seat 6, this beveled end preventing vertical displacement of the fastening block 11 without the assistance of the bolts 12 and nuts 13.

In this form of fastener, we reserve the right to use the overhanging ledge 8 at the outer end of the tie to engage the outer flange 10 of the rail 7, while the fastening block 11 is used to fasten the inner flange 9 of said rail. This arrangement is best shown at the right hand side of Fig. 1 of the drawings, and is used in connection with the confronting ends of two rails that are to be joined upon the tie.

The confronting ends of the rails 7 are jointed by splice bars 15 connected to said rails by bolts 16 and nuts 17. The splice bars 15 are cut away, as at 18, to clear the ledge 8 and the fastening block 11, said splice bars when engaging said ledge and the fastening block preventing the ends of the rails 7 from shifting upon the tie.

By reference to Fig. 4 of the drawings, it will be observed that the overhanging ledge 8 and the fastening block 11 embrace the base flanges of the rails just the same as though a single rail was fastened upon the tie without the use of splice bars, but should it be desired that the splice bars embrace the entire web of the rail 7, the overhanging ledge and the fastening block 11 can be cut away to provide clearance for the lower edges of the splice bars, as best shown in Fig. 6 of the drawings.

While in the drawings forming a part of this application there is illustrated the preferred embodiments of our invention, we would have it understood that the same can

be varied or changed as to shape, proportion and manner of assemblage without departing from the spirit of the invention.

Having now described our invention what we claim as new, is:—

1. In a metallic tie and rail fastener, the combination with rails, of a tie of the eye-beam construction, said tie comprising a base, a web, and a head provided with reinforced enlarged ends, vertical ribs arranged upon opposite sides of said tie for supporting the enlarged ends of the head thereof, the enlarged ends of said head having seats formed therein for said rails, an overhanging ledge forming part of each seat for engaging the base flanges of said rails, a fastening block mounted in each seat for engaging the base flanges of said rails, splice bars for connecting the confronting ends of two of said rails upon said seat, said splice bars having the lower edges thereof cut away to provide clearance for said ledge and said fastening block, and means extending vertically through the enlarged ends of the head of said tie for holding said fastening blocks in engagement therewith.
2. In a metallic tie and rail fastener, the combination with rails, of a tie of the eye-beam construction, said tie comprising a base, a web, and a head provided with reinforced enlarged ends, vertical ribs arranged upon opposite sides of said tie for supporting the enlarged ends of the head thereof, the enlarged ends of said head having seats formed therein for said rails, an overhanging ledge forming part of each seat for engaging the base flanges of said rails, a fastening block mounted in each seat for engaging the base flanges of said rails, means extending vertically through the enlarged head of said tie for holding said fastening blocks in engagement therewith, and means independent of the first mentioned means for preventing vertical displacement of said fastening blocks.
3. In a metallic tie and rail fastener, the combination with rails, of a tie of the eye-beam construction, said tie comprising a base, a web, and a head provided with reinforced enlarged ends, vertical ribs arranged upon opposite sides of said tie for supporting the enlarged ends of the head thereof, the enlarged ends of said head having seats formed therein for said rails, an overhanging ledge forming part of each seat for engaging the base flanges of said rails, a fastening block mounted in each seat for engaging the base flanges of said rails, means extending vertically through the enlarged head of said tie for holding said fastening blocks in engagement therewith, and means independent of the first mentioned means for preventing vertical displacement of said fastening blocks.

ing part of each seat for engaging the base flanges of said rails, a fastening block mounted in each seat for engaging the base flanges of said rails, splice bars for connecting the confronting ends of two of said rails upon said seat, said splice bars having the lower edges thereof cut away to provide clearance for said ledge and said fastening block, and means extending vertically through the enlarged ends of the head of said tie for holding said fastening blocks in engagement therewith.

3. In a metallic tie and rail fastener, the combination with rails, of a tie of the eye-beam construction, said tie comprising a base, a web, and a head provided with reinforced enlarged ends, vertical ribs arranged upon opposite sides of said tie for supporting the enlarged ends of the head thereof, the enlarged ends of said head having seats formed therein for said rails, an overhanging ledge forming part of each seat for engaging the base flanges of said rails, a fastening block mounted in each seat for engaging the base flanges of said rails, means extending vertically through the enlarged head of said tie for holding said fastening blocks in engagement therewith, and means independent of the first mentioned means for preventing vertical displacement of said fastening blocks.

In testimony whereof we affix our signatures in the presence of two witnesses.

JOHN MAJORS.

ROBERT P. FITZGERALD.
